UNITED STATES PATENT OFFICE.

WILFRED I. OHMER, OF DAYTON, OHIO, ASSIGNOR TO THE RECORDING AND COMPUTING MACHINES COMPANY, OF DAYTON, OHIO.

OPERATING MECHANISM FOR CAR-REGISTERS.

SPECIFICATION forming part of Letters Patent No. 769,398, dated September 6, 1904.

Application filed January 23, 1903. Serial No. 140,211. (No model.)

To all whom it may concern:

Be it known that I, WILFRED I. OHMER, a citizen of the United States, residing at Dayton, in the county of Montgomery and State of Ohio, have invented certain new and useful Improvements in Operating Mechanism for Car-Registers, of which the following is a specification, reference being had therein to the accompanying drawings.

10. This invention relates to operating mechanism for car-registers or, in other words, to mechanism mounted on or in a street-car body by means of which the conductor may operate at one or more points distant from the register a register mounted on the wall of the car.

15. More specifically, my invention relates to operating mechanism for use in connection with registers of that class which require two operating movements to complete their cycle of operation, one movement being for the purpose of setting the register so as to indicate and register different kinds of fare or different numbers of fare units and the other movement being the actual actuating movement whereby the registration is accomplished.

20. It is the object of my present invention to provide a simple and efficient mechanism whereby by the use of one and the same operating-handle moving in different directions both the setting and the actuating movements may be imparted to the register.

25. To these ends my invention consists in certain novel features, which I will now proceed to describe and will then particularly point out in the claims.

30. In the accompanying drawings, Figure 1 is a perspective view showing my invention applied to a street-car. Fig. 2 is a detail view 40 of a portion of the operating mechanism. Fig. 3 is a vertical sectional view taken on the line xx of Fig. 2 and looking in the direction of the arrows. Fig. 4 is a vertical sectional view taken on the line yy of Fig. 3 and looking in the direction of the arrows. Fig. 5 is a detail sectional view taken on the line zz of Fig. 3 and looking in the direction of the arrows, and Fig. 6 is a plan view of the

housing and its inclosed mechanism removed from the supporting-bracket.

50. Referring first to the construction shown in Figs. 1 to 6, inclusive, 1 indicates a fare-register, which is mounted, as usual, on one of the end walls of the car, so as to be maintained in fixed position thereon when in use. This register is provided with a setting-arm 2, by means of which the mechanism of the register may be set to register and indicate either different numbers of fare units or different kinds of fares. The register is further provided with an actuating-lever 3, by means of which the register is operated after being set to register the fare or fare units to which it has been set. Registers of this class are well known, and any approved form thereof may 65 be employed.

4 indicates an operating-shaft, constituting in the present instance both a setting and an actuating shaft and mounted in suitable bearings supported from the car-body, along which it extends adjacent to the roof in the position usual for such devices. In the present instance I have shown a support for the shaft consisting of a bracket 5, depending from the roof, and a housing 6 in the form of a hollow 70 box, open at the top and secured to the under side of the bracket 5 by means of screws 7, the bottom plate 8 of the bracket forming a cover or top for the housing 6. It will be understood, of course, that any desired number of these supports may be employed, and an operating-handle and connecting mechanism may be employed in connection with each support, so that the shaft 4 may be operated from any part of the car.

80. Referring now particularly to the operating-handle and connecting mechanism, 9 indicates the operating-handle, which is mounted to slide vertically upon a shaft 10, which is mounted in a suitable bearing in the bottom of the housing 6. The movement of the handle is longitudinal with respect to the shaft, and a spline-and-groove connection between the two permits the handle to move freely longitudinally of the shaft, while the shaft is compelled to turn when the handle is

rotated. The shaft 10 is provided at its upper end with a bevel-gear 12, which meshes with a similar bevel-gear 13, carried by a sleeve 14, mounted in a suitable bearing in the side wall of the housing and having a spline-and-groove connection 15 with the shaft 4, so that said shaft may slide freely with respect to the bevel-gear 13, but will rotate along with said gear. Thus a rotary movement of the operating-handle 9 will rotate the shaft 4, and said shaft is provided at a point adjacent to the register 1 with an operating-arm 16, in the path of which the setting-arm 2 of the arm lies, so that by rotating the handle 9 the setting-register 2 may be moved to set the register to the desired position.

I prefer to employ in connection with the operating-handle and shaft one or more indicators, preferably one for each operating-handle, and to this end I provide an indicating-wheel 17, carrying on its face numbers indicating the fare units or other suitable designating characters. This indicating-wheel is mounted on a shaft 18, which is mounted in a suitable bearing in the front wall of the housing 6 and which is provided at its rear end with a bevel-gear 19, which meshes with the bevel-gear 12. Thus as the conductor turns the handle 9 the indicator-wheel will be revolved into indicating position for the proper figure or character to designate the fare which the register has been set to register by the corresponding movement of the handle, and the conductor can thus readily see that the register is properly set.

After the register has been set by a movement of the handle 9 in one direction—to wit, a movement of rotation—the register is then actuated by a movement of the handle in another direction—to wit, a longitudinal downward movement. To this end the handle is provided with a cord, wire, or other suitable connection 20, which extends up from the handle through a longitudinal opening 21 in the shaft 10 and bevel-gear 12 and is connected at its upper end to one end of a bell-crank lever 22, pivoted at 23 on a supporting stud or projection within the housing 6. The other end of the bell-crank lever is forked to embrace the shaft 4 and is slotted, as indicated at 24, and into these slots extend projections 25, from a collar 26, mounted on the shaft 4 in such a way as to permit the shaft to rotate freely within the collar, while causing the shaft to move longitudinally along with the collar. It will be seen that the downward motion of the operating-handle will impart a longitudinal motion to the shaft 4, and said shaft is provided with a collar 27, in the path of which lies the actuating-arm 3 of the register, so that this longitudinal movement of the shaft will actuate the register and cause it to register and indicate the number of fare units to which it has been set.

The parts may be returned to their normal position by springs or the like suitably arranged, and in the present instance this is effected by means of the springs which return the register-arms 2 and 3 to their normal positions.

It will be seen that both the setting and actuating movements of the register are accomplished by the use of one and the same handle, so that the conductor does not need to change or shift his grasp to effect both movements. It will further be seen that an indicating device is provided adjacent to the operating-point, so that the conductor can readily and distinctly see that the register is properly set, which would not be the case if he were operating the register from a considerable distance and had to rely upon the indicating-figures shown by the register itself, these figures being frequently small and difficult to make out at a distance or in a crowded car.

While I have shown and described one embodiment of my invention, I do not wish to be understood as limiting myself to the precise embodiment set forth, since various modifications will readily suggest themselves. The indicating wheel or wheels may be located at any suitable point and operated by any suitable connecting mechanism. I also prefer to employ a register provided with an indicator 32, which will indicate on the register itself, as well as on the auxiliary indicating wheel or wheels, the particular fare for which the register is set and which will serve as a check to insure the correspondence between the indicating-wheels of the operating mechanism and the proper setting of the register. The details of the mechanism may also be varied without departing from the principle of my invention. I therefore do not wish to be understood as limiting myself to the precise details hereinbefore set forth, and shown in the accompanying drawings.

Having thus fully described my invention, what I claim as new, and desire to secure by Letters Patent, is—

1. An operating mechanism for car-registers, comprising a shaft capable of both rotary and longitudinal motion, a housing in which said shaft is mounted, a vertical shaft mounted in said housing and having a geared connection with said shaft within said housing, whereby both of said shafts rotate in unison, an operating-handle mounted on said vertical shaft so as to rotate therewith, and movable longitudinally thereof, a bell-crank lever mounted in the housing and engaging the shaft to move the same longitudinally, and a connection between the operating-handle and the bell-crank lever to actuate said lever when the handle is moved longitudinally, substantially as described.

2. The combination, with a register and provided with setting mechanism and an ac-

tuating mechanism, of a rock-shaft capable of longitudinal and rotary motion and provided with means to actuate the setting mechanism during its rotary motion, and with means to 5 actuate the actuating mechanism during its longitudinal motion, a housing supporting the shaft, a bevel-gear mounted in the housing and splined on the shaft, a vertical shaft mounted in the housing and provided with a 10 bevel-gear to mesh with the first-mentioned gear, an operating-handle splined on said vertical shaft and longitudinally movable relative thereto, a bell-crank lever mounted in the housing and engaging the shaft to move 15 the same longitudinally, and a connection between the operating-handle and bell-crank lever to actuate said lever when the handle is moved longitudinally, substantially as described.

20 3. The combination, with a register provided with a setting-arm and an actuating-arm, of a rock-shaft capable of longitudinal and rotary motion and provided with a projection to engage the setting-arm during its 25 rotary motion, and with a projection to engage the actuating-arm during its longitudinal motion, a housing supporting the shaft, a bevel-gear mounted in the housing and splined on the shaft, a vertical shaft mounted in the 30 housing and provided with a bevel-gear to mesh with the first-mentioned gear, an operating-handle splined on said vertical shaft and longitudinally movable relatively thereto, a bell-crank lever mounted in the housing and

engaging the shaft to move the same longitudinally, and a connection between the operating-handle and bell-crank lever to actuate said lever when the handle is moved longitudinally, substantially as described. 35

4. The combination, with a register provided with a setting-arm and an actuating-arm, of a rock-shaft capable of longitudinal and rotary motion and provided with a projection to engage the setting-arm during its rotary motion, and with a projection to engage the actuating-arm during its longitudinal motion, a housing supporting the shaft, a bevel-gear mounted in the housing and splined on the shaft, a vertical shaft mounted in the housing and provided with a bevel-gear to 50 mesh with the first-mentioned gear, an operating-handle splined on said vertical shaft and longitudinally movable relatively thereto, a bell-crank lever mounted in the housing and engaging the shaft to move the same longitudinally, a connection between the operating-handle and bell-crank lever to actuate said lever when the handle is moved longitudinally, and an indicator having a shaft mounted in the housing and provided with a bevel-gear meshing with the bevel-gear of the vertical shaft, substantially as described. 55

In testimony whereof I affix my signature in presence of two witnesses.

WILFRED L. OHMER.
